ASHLEY SEIGBERT MACLEAN, OF WEMBLEY PARK, ENGLAND.

MACHINE FOR AFFIXING ADHESIVE LABELS.

Application filed April 16, 1928, Serial No. 270,478, and in Great Britain February 28, 1928.

This invention relates to machines for affixing adhesive labels and has particular reference to such machines designed for affixing postage stamps to envelopes and the like, and 5 it has for its object a construction which is of a simple and robust nature, is relatively cheap to produce, and which can be handled with ease and celerity.

I attain these ends by combining with any 10 suitable form of mechanism for feeding strips of stamps or other labels and for damping same as they are delivered, a platform adapted to receive one by one the envelopes or other packets to which the label is to be fixed, said 15 platform being arranged in front of the delivery side of the feeding and damping device and preferably having guides on its rear edge and one of its sides for the purpose of 20 positioning the envelopes or the like as and when they are placed on the platform. In front of the platform is mounted a plunger which is connected with the driving mechanism of the feeding device which is adapted to operate same when it is pressed inwards. 25 The corner of the platform immediately in front of the feeding device is cut away to form a recess or aperture to enable the operator to grip the envelope and the stamp delivered on to it—by the operation of the afore- 30 said plunger—above and below between the thumb and forefinger of one of his hands and thereby exert the necessary pressure to cause the stamp to adhere to the envelope, and subsequently, without removing his hold, remove 35 the envelope from the platform and at the same time detach the stamp from the strip.

The present invention also embraces operating the feeding device by a movement of the platform.

40 In the drawing which illustrates a machine constructed according to the present invention for stamping envelopes and the like:— Figures 1, 2 and 3, are views in plan, in side elevation and in front elevation respectively 45 of a complete machine arranged to deliver the stamps at the left-hand side of the platform.

Throughout the views similar parts are marked with like numerals of reference.

On a suitable base 1 is mounted the stamp 50 delivery mechanism which may be of any

suitable type to deliver stamps one by one from a roll. The mechanism illustrated comprises a spindle 2 for carrying the roll of stamps, drawing rollers 3 and 4, a guide roller 5, a damping roller 6, mounted in a trough 7, 55 a ratchet and pawl driving gear 8, a train of gearing 9, 10, and 11, driving the rollers 3 and 5, and a rocking lever 12 operating the ratchet and pawl gear.

In front of the delivery side of the stamp 60 delivery mechanism is a platform 13 mounted on the base 1 with its rear edge in close proximity to the delivery orifice of said mechanism. The rear and left-hand edges of the platform are preferably provided with stops 65 to position the envelopes or the like as they are placed on it, which stops may conveniently take the form of flanges 14 and 14^x. The left-hand rear corner of the platform 1 is cut away in front of the delivery orifice to form a re- 70 cess or aperture 15 which will allow the operator to grip both the envelope and the stamp and exert the necessary pressure to cause them to stick together and obtain a hold on the envelope for the purpose of lifting the en- 75 velope from the platform and at the same time detaching the stamp from the strip.

Any suitable means may be provided for actuating the stamp delivery mechanism the preferred means being such as can be operated by the hand of the operator that places the article to be stamped on the platform. Such a means is shown in the accompanying drawing and comprises a sliding plunger 16 mounted under the platform 1 which is coupled to the rocking lever 11 of a sliding plunger 80 85 or the actuating device of the stamp delivery mechanism and is provided with a suitably shaped presser plate 17 which lies in front of the front edge of the platform. 90

In use the operator takes up by his right hand an envelope from a pile and places it in the platform pressing it up against the guides on the rear and left-hand edges by his forefingers and at the same time by exerting pressure on the presser plate of the plunger by his thumb imparts the necessary motion to the roll of stamps to deliver a stamp 95 on to the envelope.

As soon as the stamp has been delivered 100

the operator grips the stamp and the envelope by the thumb and forefinger of his left-hand—through the recess or aperture 15—and presses them together at the same time lifting the envelope from the platform by a slight twisting movement which will detach the stamp from the strip.

It will be appreciated that with this machine the hand of the operator used for placing the envelope on the platform is also used for actuating the feed delivery mechanism while the other hand is used for pressing the stamp on the envelope, for withdrawing the envelope from the platform and for detaching the stamp from the strip whereby a considerable amount of mechanism is dispensed with without minimizing the speed at which the machine can be worked.

It will be understood that whereas the machine illustrated is a right-hand machine it may be made left-handed by reversing the positions of the stamp delivery mechanism and the cut-away part of the platform relative to the platform, and it will be obvious that the shape and size of the recess or aperture 15 in the platform 13 may be varied within limits.

What I claim is:—

1. A machine for affixing adhesive labels comprising mechanism for feeding the labels and for damping the adhesive sides of same, a platform in front of the feeding mechanism having a portion in front of the delivery side of said feeding mechanism cut away to form a recess or aperture open to the adjacent side of the platform, and means for imparting motion to the feeding mechanism.

2. A machine for affixing adhesive stamps comprising a device for feeding and damping a strip of stamps, a platform in front of the feeding and damping device having a portion immediately in front of said device cut away to form a recess or aperture open to its adjacent side, guide flanges on said platform, and hand operated mechanism for imparting motion to the feeding gear.

3. In a machine for affixing adhesive labels the combination of a roller adapted to support a rolled strip of labels, drawing rollers for imparting a feeding motion to said strip, a damping roller over which the labels pass, a ratchet and pawl gear for imparting motion to the drawing rollers, a platform in front of the strip delivery mechanism having a portion in front of the damping roller cut away to form a recess or aperture open to its adjacent side, and hand operated means for imparting motion to the feed gear.

4. In a machine for affixing adhesive labels the combination of a roller adapted to support a rolled strip of labels, drawing rollers for imparting motion to said strip, a damping roller over which the strip of labels passes, a roller for keeping the strip in contact with the damping roller, a ratchet and pawl gear for

imparting motion to the drawing rollers, a platform in front of the strip delivery mechanism having a portion in front of the damping roller cut away to form a recess or aperture open to its adjacent side and means for imparting motion to the ratchet and pawl gear capable of operation by the same hand that places the article to which the label is to be affixed on the platform.

5. In a machine for affixing adhesive labels the combination of a roller adapted to support a rolled strip of labels, drawing rollers for imparting motion to said strip, an absorbent damping roller over which the strip of labels passes, a roller for keeping said strip in contact with the damping roller, a water trough into which the damping roller dips, a ratchet and pawl gear for imparting motion to the drawing rollers, gearing for coupling the roller coacting with the damping roller with one of the drawing rollers, a platform in front of the strip delivery mechanism having a portion in front of the damping roller cut away to form a recess or aperture open to its adjacent side, guides on said platform, and means for imparting motion to the ratchet and pawl gear capable of operation by the hand that places the article to which the label is to be affixed on the platform.

6. A machine for affixing stamps comprising a roller adapted to support a rolled strip of stamps, drawing rollers for imparting motion to said strip, a damping roller over which said strip passes, a roller for keeping said strip in contact with the damping roller, a water trough into which the damping roller dips, gearings for driving said drawing rollers, a ratchet and pawl gear for imparting motion to said gearing, gearing for coupling the roller coacting with the damping roller with one of the drawing rollers, a platform in front of the stamp delivery mechanism having a portion in front of the damping roller cut away to form a recess or aperture, guides on two edges of said platform, and a plunger mounted under said platform which is in couple with the ratchet and pawl gear of the feeding mechanism.
